UNITED STATES PATENT OFFICE.

WERNER LAUPPI AND LESLIE BERTANYI, OF PORTLAND, OREGON.

ADVERTISING DEVICE.

Application filed April 2, 1928. Serial No. 266,701.

This invention relates to advertising devices and embodies among other characteristics a revolvable element adapted to display different advertising matter at predetermined 5 intervals in the rotation thereof.

Another object of the invention embodies a housing for the rotatable element having a sight opening therein through which the advertising matter may be seen.

10 An additional object of the invention contemplates an operating mechanism for the rotatable element adapted to rotate the rotatable element predetermined distances to expose the different faces thereof through 15 the sight opening.

A further object of the invention comprehends a stop mechanism adapted to sustain the different faces of the rotatable element adjacent the sight opening.

20 More specifically stated, the sight opening is adapted to be illuminated when the different faces of the rotatable element are exposed.

With the above and other objects in view, 25 the invention further consists of the following novel features and details of construction, to be hereinafter more fully described, illustrated in the accompanying drawings and pointed out in the appended claims.

30 In the drawings:—

Figure 1 is an elevation of the invention.

Figure 2 is a vertical sectional view taken on line 2—2 of Figure 1.

Figure 3 is a horizontal sectional view 35 taken on line 3—3 of Figure 2.

Figure 4 is a sectional view taken on line 4—4 of Figure 3.

Figure 5 is a sectional view taken on line 5—5 of Figure 3.

40 Referring to the drawings in detail, wherein like characters of reference denote corresponding parts, the reference character 10 indicates a platform supported upon legs 11. A motor 12, carried upon the upper side 45 of the platform, is retained thereon by a clamping band 13. Said motor is provided with a worm drive shaft adapted for meshing engagement with a worm gear 14 rotating a fixed upstanding shaft 15 carrying a 50 spur gear 16 upon the uppermost end thereof.

A gear member 17, horizontally disposed and rotatably mounted upon an upper end 55 of a standard 18, upstanding from the upper surface of the platform 10, is adapted for meshing engagement with the spur gear

16. A rotatable housing 19 of cross section pentagon shape is provided with a cone-shaped top 20, including a bar member 21 upon the underside of the apex thereof to 60 journal the uppermost end of a shaft member 22. A reduced extension 23, depending from the lowermost end of the shaft 22, is positioned within a socket opening 24 in the uppermost end of a shaft member 25 65 upstanding from and disposed centrally of the platform 10. A pin member 26, extended horizontally through the socket opening 24 in the reduced extension 23 of the shaft 22 therein, is adapted to provide a fixed connection therebetween. The lowermost end of the shaft 25 being rigidly connected with the platform 10. A bearing member 27, interposed between the connecting portions of the shafts 22 and 25 respectively, is adapted 70 to support a hub member 28. Spokes 29, radially disposed from the hub 28, are adapted for connection with the inner faces of the rotatable element 19.

An elongated set screw 30, passed through 80 one of the faces of the rotatable element 19, is adapted to be horizontally disposed within the hub member 28 and which is adapted to engage the bearing member 27 at the innermost end thereof. The opposite end of the 85 particular set screw extends through an opening in one of the faces of the rotatable element and is provided with a cross pin 31 located immediately behind said face to restrict retracting movement of the set screw 90 per se whereby the latter may not become displaced when the same is loosened. Such construction will prevent the hub member 28, spokes 29 and rotatable element 19 from rising and falling from a given position. 95

As noted, the hub member 28 is free to rotate upon the bearing 27.

A cylindrical housing member 32, having a cone-shaped top 33 and disposed in spaced relation to the outer faces and intersecting 100 portions of the respective faces of the rotatable element 19, is provided with a sight opening 34 through which said faces may be exposed.

Frame members 35, carried upon the outer 105 sides of the rotatable element 19, are adapted to retain cards, pictures or other advertising matter, such as indicated at 36, against the respective faces thereof.

A finger 37, axially mounted upon the 110 upper side of the gear 17, is adapted for selective engagement with the bevel faces

38 upon the innermost projecting ends of L-shaped arms 39 carried upon the inner side of the rotatable element and between the intersections of the respective faces 5 thereof.

From the illustration in Figure 3 of the drawings, it is to be noted that further rotation of the gear 17 will cause the adjacent L-shaped arm 39 to be moved in the direction of the arrow whereby a different face of the rotatable element will be brought into registration with the sight opening 34 in the housing 32.

Due to the fact that the hub member 28 is free to rotate upon the bearing member 27, it is desirous to have the different faces of the rotatable element stopped at many intervals to display the different advertising matter carried upon the faces thereof 20 through the sight opening. To this end, I provide a sleeve member 40 upstanding from the platform 10 and within which is mounted a reciprocating pin 41 encircled by a compression spring 42 adapted to normally 25 dispose the pin to occupy the position as best illustrated in Figure 5 of the drawings. A pin 43, carried by and horizontally disposed from the uppermost end of the pin 41, is adapted for reciprocating action within 30 a cut-out portion or portion removed, such as indicated at 44, to normally dispose the beveled face 45 upon the uppermost end thereof in the position shown, the purpose of which will be presently apparent. 35 An arm 46, pivotally mounted for lateral swinging movement, as indicated at 47, upon the upper side of the platform 10 and toward and away from the sleeve member 40, is adapted for connection with a retractile 40 spring 48 adapted to normally dispose said arm to occupy the position shown in spaced relation to the beveled end 45 of the pin 41. The space between the end of the arm 46 and the beveled face 45 of the pin 41 is equivalent to that of the width of any one 45 of the L-shaped arms 39.

When any one of the L-shaped arms 39 are engaged by the finger 37 upon the gear member 17 and rotated an appreciable distance, the next succeeding face of the rotatable element 19 is disposed in juxtaposition immediately behind the sight opening 34 in the housing 32, simultaneously with the disposing of the next succeeding L-shaped arm 39 between the uppermost end of the arm 46 and the beveled end 45 of the pin 41, whereby the particular face of the rotatable element will be held against further rotation and the same will remain in such position long enough to permit reading of the particular card. The sight opening 34 is surrounded by a multiplicity of illuminating devices 48 connected in circuit with a switch member 49. Spring contact arms 50, 60 having connection with the terminal wires

connecting the illuminating devices 48 with the switch 49, are disposed in spaced relation to connect the illuminating devices in normally open circuit.

Contact members 51, laterally projected from the lowermost ends of the L-shaped arms 39 and extended through the rotatable element 19, are adapted to selectively bridge the gap between the respective spring contact fingers 50 to close the circuit between the switch and illuminating devices 48 when any one of the faces of the rotatable element is disposed in juxtaposition to the sight openings 34. When the gear 17 completes another revolution, the next succeeding L-shaped arm 39 is engaged and the particular contact member 51 is moved away from the spring contact fingers 50 and the illuminating devices 48 will consequently shut off during the time a new ad face is being moved into position.

The invention is susceptible of various changes in its form, proportions and minor details of construction, and the right is herein reserved to make such changes as properly fall within the scope of the appended claims.

Having described the invention, what is claimed is:—

1. An advertising device comprising a rotatable element having a multiplicity of faces, a housing for the rotatable element being provided with a sight opening, an operating mechanism, a gear member operable by the operating mechanism, a finger carried by and eccentrically mounted upon said gear, and arms carried by the rotatable element adapted for engagement with said finger to facilitate rotation of the element and the exposition of the different faces thereof.

2. An advertising device comprising a rotatable element having a multiplicity of faces, a housing for the rotatable element being provided with a sight opening, an operating mechanism, a gear member operable by the operating mechanism, a finger carried by and eccentrically mounted upon said gear, arms carried by the rotatable element adapted for engagement with said finger to facilitate rotation of the element and the exposition of the different faces thereof, and a stop mechanism adapted to retain the faces adjacent the sight opening to permit reading of advertising matter thereon.

3. An advertising device comprising a rotatable element having a multiplicity of faces, a housing for the rotatable element being provided with a sight opening, a gear member rotatable within said element being provided with an eccentrically mounted finger, arms carried by the rotatable element being adapted for engagement with said finger to transmit the necessary motion to

the element, a pin located in the path of movement of said arms and exposing a beveled end thereto, a spring seating the pin and a trip arm operable in conjunction with the pin being adapted to retain the adjacent arm therebetween to stop the rotatable element to expose the different faces thereof through the sight opening.

4. An advertising device comprising a rotatable element having a multiplicity of faces, a housing for the rotatable element being provided with a sight opening, a gear member rotatable within said element being provided with an eccentrically mounted finger, arms carried by the rotatable element being adapted for engagement with said finger to transmit the necessary motion to the element, a pin located in the path of movement of said arms, an arm member pivotally mounted for lateral swinging movement toward and away from said pin and spaced from the latter to dispose and hold an adjacent arm therebetween, a stop for the arm member, illuminating devices surrounding the sight opening in the housing, and contact members operable in conjunction with each of the arms being adapted to close the circuit with the illuminating devices when the different faces of the rotatable element are disposed in juxtaposition to the sight opening.

In testimony whereof we affix our signatures.

WERNER LAUPPL
LESLIE BERTANYI.
